WINDOW OR WALL VENTILATOR

Willem Hendrik Braskamp, Voorburg,
NetherlandsApplication February 13, 1951, Serial No. 210,720
In the Netherlands February 17, 1950

3 Claims. (Cl. 268—97)

1. The present invention relates to a window or wall ventilator, comprising a movable shutter for obturating the air passage at will.

The invention is more particularly concerned with the mechanism for operating such shutter and has for its object to so design such mechanism that displacement of the shutter, in either direction, may be effected or initiated by exerting an operating force which has the same direction for both directions of movement of the shutter.

To this end the invention provides a window or wall ventilator comprising in combination a movable shutter for obturating the air passage, a member for operating such shutter, a snap pawl for blocking said shutter operating member in one end position thereof against movement by a return force, a pawl lifting member adapted to rock on an axis carried by said shutter operating member and means for exerting on said pawl lifting member, at a certain point of incidence, an operating force in a direction opposite to said return force, said pawl lifting member, in free condition, tending to take up a position in which the point of incidence of said operating force lies beyond said rocking axis at the side facing said snap pawl, and in the other end position of said shutter operating member, by cooperation with an abutment, is held against such tendency in a position in which said point of incidence is beyond said rocking axis at the opposite side thereof all in such a manner, that upon exertion of the operating force in the blocked end position of the shutter operating member, said pawl lifting member is rocked to lift said snap pawl and upon exertion of a similarly operating force in the other end position of the operating member, is rocked in a direction to engage the operating member and transmit the operating force thereto.

More particularly, according to a further characteristic feature of the invention said pawl lifting means may consist of a spring loaded U-shaped element, pivotally straddling one arm of a bell crank lever functioning as the shutter operating element, such bell crank lever being adapted to exert an operating force on said shutter against the action of a spring, said U-shaped element at the point of attack of the operating force having a pulling member attached thereto.

The invention will hereinafter be further described with reference to the accompanying drawing.

Fig. 1 is a side elevational view partially in section, of a portion of a window or wall ven-

2. A window or wall ventilator comprising a shutter operating mechanism, arranged in accordance with the present invention.

Fig. 2 is a detailed sectional perspective view of a portion of Fig. 1.

The ventilator 1 to be arranged in an opening of a window or wall, is provided with a hood 2 serving as a shutter for the air passage and arranged for cooperation with the edge of a ventilator frame portion, such hood being shown in full lines in the closed position and in dotted lines in open position.

The hood 2 is mounted to slide in guideways 3 of the ventilator frame and is provided with a pin 4 engaged by the forked end of a bell crank lever 5, 5' serving as shutter operating element and being pivotally mounted on a fixed axis 6, such bell crank lever being acted upon by a torsion spring 7 surrounding said axis 6 and in the embodiment shown being arranged to urge said bell crank lever in a direction in which the shutter is caused to open the air-passage.

In the closed position of the shutter, as shown in full lines, the lever 5, 5' is held against the action of the spring 7, by a pawl formed as a curved blade spring 8, which on the one hand is attached to the ventilator casing and on the other hand resiliently engages a recess 9 formed in the free end of the arm 5', of the bell crank lever. Beneath said recess, the arm 5' is provided with a rounded nose 10, designed for acting upon the blade spring in a manner further to be described.

The arm 5' of the bell crank lever further carries at a short distance from its free end, a U-shaped element 11, which from above straddles said lever arm and is pivotally connected thereto by a short stud 12 surrounded by a torsion spring 13, which normally urges said U-shaped element to pivot in clockwise direction as seen in the drawing. This angular movement is limited by an abutment pin 14, carried by said bell crank lever. The element 11 at the point of incidence 15 has attached thereto a chain or other pulling member 16 on which the operating force is to be exerted. This point of incidence 15 is so selected, that in the free position of the element 11, that is in the position reached by its clockwise angular displacement, it is situated beyond the stud 12 at the side facing the pawl 8. In this position the respective edge of the element engages the pawl spring, however with a pressure, which is insufficient to overcome the force of the spring. In this position the element 11 is still free from the abutment pin 14.

Departing from the full line or blocked position of the bellcrank lever in the embodiment shown corresponding to the closed position of the shutter, an operating force exerted on the chain 16 will first cause the element 11 to further rock in clockwise direction, causing the pawl spring to be disengaged from the recess 9, thereby releasing the bell crank lever, so that upon release of said chain, the torsion spring 7 will move the bell crank lever into its dotted line position, corresponding with opened shutter, since the rounded nose 10 is then able to pass the pawl spring.

Near the end of the opening movement of the bell crank lever, the upper lefthand corner of the element 11 engages an abutment, which, in the embodiment shown, is formed by the ventilator casing, thereby causing rocking of the element 11 in anti-clockwise direction towards its dotted position, the point of incidence 15 of the pulling chain 16 then being to the left of the stud 12. In this position the element 11 is held.

In order to close the air passage, one only needs to again exert a pulling force on the chain 16, causing the element 11 to rock anti-clockwise (compare lower dotted position of the element 11) said element thereby engaging the arm 5' of the bell crank lever and transmitting the operating force thereto, causing the shutter to be moved towards the right, against the action of the torsion spring 7, that is causing the shutter to open the air passage.

During this movement of the bell crank lever about its axis, the rounded nose 10 forces the blade spring back, whereupon such spring again snaps into the recess 9 for blocking the shutter in closed position.

What I claim is:

1. A ventilator comprising a frame element having an opening therein, a shutter movable

between a position obturating said opening and a position giving free passage for air passing therethrough, a shutter operating member mounted on said frame for movement between two end positions corresponding to the closed and open positions of said shutter, spring means acting on said operating member to urge said member toward one of its end positions, a pawl positioned to engage said member and retain it against the action of said spring when in its other end position, a pawl-lifting member pivotally mounted on said operating member, actuating means for exerting on said pawl-lifting member an actuating force in opposition to said spring means, the pivotal mounting of said pawl-lifting member on said operating member being such as to enable rocking movement of said pawl-lifting member between positions where the point of exertion of the actuating force is situated on either side of the pivotal axis of said mounting, and a spring urging said pawl-lifting member to one of said positions in contact with said pawl.

2. A ventilator as in claim 1 wherein the shutter operating member is in the form of a bellcrank lever pivoted on the frame element and having one end operatively connected to the movable shutter, the pawl-lifting member being U-shaped and pivoted adjacent the other end of the bell-crane lever.

3. A ventilator as in claim 2 wherein the U-shaped pawl-lifting element is pivoted to swing from a position inward of its point of pivotal attachment to the bell-crane lever and abutting therethrough to a position outward of said attachment point and embracing at least part of the adjacent end of said lever.

WILLEM HENDRIK BRASKAMP.
